UNITED STATES PATENT OFFICE.

EDWIN OSTBY, OF HANIKINSON, NORTH DAKOTA.

PENHOLDER.

1,066,417.

Specification of Letters Patent.

Patented July 1, 1913.

Application filed August 30, 1912. Serial No. 717,934.

To all whom it may concern:

Be it known that I, EDWIN OSTBY, a citizen of the United States, residing at Hankinson, in the county of Richland, State of North Dakota, have invented certain new and useful Improvements in Penholders; and I do hereby declare the following to be a full, clear, and exact description of the invention, such as will enable others skilled in the art to which it appertains to make and use the same.

The present invention is directed to improvements in pen holders, and has for its object to so construct a device of this character that the pen may be removed from the holder when the same has become useless without soiling the fingers.

With these and other objects in view, this invention resides in the novel features of construction, formations, combinations and arrangements of parts to be hereinafter more fully described, claimed and illustrated in the accompanying drawing, in which:—

25 Figure 1 is a side elevation of the device. Fig. 2 is a longitudinal sectional view through the same. Fig. 3 is a sectional view on line 3—3 of Fig. 1. Fig. 4 is a detail perspective view of the spring.

30 Referring to the drawing, the numeral 1 designates a handle having secured to one end the metallic barrel 2, said barrel having a longitudinal slot 3 formed in its upper surface, the purpose of which will appear later. Contained within the barrel is a leaf spring 4, which has its body portion 5 disposed obliquely within the barrel, the inner end of said body portion terminating in an extension 6 which passes through the slot 3 and is slidable therein. Secured to the

outer end of the extension 6 is a button 7 which when engaged by the finger will move the spring 4 backwardly and forwardly within the barrel 2. The outer end of the body portion 5 terminates in a reversibly 45 bent plate 8, the same being concavo-convex in cross section, and adapted to engage the pen point to hold the same firmly clamped against a portion of the barrel 2. From this construction it will be seen that a pen 50 point may be conveniently inserted between the plate 8 and barrel 3 and after the same has become useless it may be removed upon sliding the spring 4 forwardly.

A lip 9 is formed integral with the plate 55 8 and is adapted to prevent the pen point from being inserted too far in the barrel 2, said lip also serving to positively eject the pen point when the plate 8 is moved forwardly. 60

What is claimed is:—

A pen holder comprising a barrel having a longitudinal slot formed in its upper surface, a leaf spring having its body portion arranged diagonally within the barrel, the 65 inner end of said spring terminating in an extension which engages in said slot, a button secured to the outer end of the extension, the outer end of said body portion terminating in a reversibly bent plate, said plate being concavo-convex in cross section, and having a lip formed upon its inner end and slidably engaging the interior of the barrel, as and for the purpose set forth. 70

In testimony whereof, I affix my signature, in presence of two witnesses. 75

EDWIN OSTBY.
